UNITED STATES PATENT OFFICE.

FRED V. HART, OF LYNN, MASSACHUSETTS, ASSIGNOR, BY MESNE ASSIGNMENTS, TO
UNITED SHOE MACHINERY CORPORATION, OF PATERSON, NEW JERSEY, A CORPO-
RATION OF NEW JERSEY.

FEED MECHANISM.

1,352,747.

Specification of Letters Patent. Patented Sept. 14, 1920.

Application filed May 22, 1916, Serial No. 99,259. Renewed November 17, 1917. Serial No. 202,643.

To all whom it may concern:

Be it known that I, FRED V. HART, a citizen of the United States, residing at Lynn, in the county of Essex and State of Massachusetts, have invented certain new and useful Improvements in Feed Mechanism; and I do hereby declare the following to be a full, clear, and exact description of the invention, such as will enable others skilled in the art to which it appertains to make and use the same.

This invention relates to the feeding of pieces of heel material which are tapering or non-uniform in thickness, and it has special reference to method of and means for feeding pieces of sheet heel material that are of wedge-shaped or uniformly tapering cross-section, such as the ordinary dinked or polygonal wedge lifts employed in the formation of shoe-heels, or the elongated tapering strips from which such lifts are cut.

In feeding flat or uniformly thick pieces of heel material whether in sheet form or otherwise, it is common to stack such pieces in face-to-face relation in a suitable straight magazine which is substantially the size or slightly larger than the pieces themselves, and to eject them successively from one end of the magazine. This mode of operation is easily carried out when the pieces are flat or uniform in thickness, as they will stack in substantially parallel positions when lying loosely the one against the other, either in superposed or in side-by-side relation. Moreover, they will maintain and preserve this substantially fixed relation while being freely fed through the magazine.

However, when pieces of sheet heel material that are tapering or irregular in thickness are stacked loosely the one against the other in the manner and by the means employed in the prior art for feeding flat pieces, the pieces will, by reason of their tapering character, tend to stack radially the one against the other, thus crowding or jamming the pieces in the magazine and preventing the pieces from being fed freely and uniformly. For instance, if a vertical straight magazine of substantially the size

or slightly larger than the pieces to be operated upon, be employed in the way common to flat or uniformly thick pieces or lifts, the radial formation, above referred to, becomes prohibitive and blocks the free feeding when more than relatively few pieces are stacked. In fact, the number of tapering pieces that can be stacked and fed in the manner of the prior art is so few as to be entirely impracticable and useless in a commercial machine.

The successful operation of such a machine requires a simple and practical mechanism for feeding stacks of tapering lifts or strips of sheet material, in which stacks of indeterminate length may be loaded in position in the magazine and fed therefrom with regularity and facility, whereby only a moderate amount of attention and relatively infrequent loading of the machine is demanded of the operator.

Obviously, no particular length of stack is necessary, although for most satisfactory operation, it should be capable of being materially greater than the very restricted length of radially disposed pieces that can be handled in the manner and by the means that have been heretofore employed for feeding flat lifts or pieces of sheet-material. The construction and arrangements of parts must, however, be such that the tapering lifts or pieces may be uniformly stacked to any reasonable and indeterminate length, and be successfully fed while maintaining their relative substantially fixed relationship. For commercial operation, the stack is preferably long, but if desired, may be relatively short. In this sense, the requisite characteristic of the stack is that it is indeterminate in length, and that the several tapering pieces which compose it shall be so positioned as to maintain a substantially fixed mutual relationship throughout the feeding operation.

One object of the invention, therefore, is to provide a method of feeding pieces of sheet heel material, that are tapering or otherwise irregular in one dimension, from a stack of indeterminate length in which the central plane of each piece bears a fixed

relation to the central planes of the contiguous pieces, which method involves advancing such a stack in the direction of its length while maintaining the pieces in fixed 5 mutual relationship, and removing the pieces successively from the end of the stack to which they are fed.

Another object of the invention is to provide a feed-mechanism in which lifts or 10 pieces of sheet heel material, that are tapering or otherwise irregular in one dimension, may be stacked to an indeterminate length in proper relation to each other that they may be freely fed and ejected or removed 15 from one end of the stack, while maintaining a substantially fixed mutual relationship throughout the operation.

To the foregoing ends, one illustrative embodiment of the invention contemplates a 20 construction and arrangement and location of parts such that a plurality of tapering, or otherwise non-uniform pieces of sheet heel material may be stacked to an indeterminate length in face-to-face relation with their 25 thick ends in engagement and their thin ends positively and individually spaced apart so as to secure and preserve a substantially definite and fixed parallel relation of the component elements of the stack.

30 In accordance with this embodiment of the invention, pieces of the kind in question are stacked in approximately parallel face-to-face relation in an upright or inclined magazine having two parallel walls 35 that are spaced from each other by a distance which is substantially less than the dimension of the pieces which is normal to the dimension in which the pieces taper or are of non-uniform thickness. The pieces are 40 placed between these walls in inclined positions with their thick ends in engagement and supported the one upon the other, against one of the walls of the magazine, and their thin ends resting or leaning against 45 the other wall thereof, whereby they are positively spaced apart and their central planes are maintained in approximately parallel relation throughout the feeding and ejecting or removing operation.

50 Although, for illustrative purposes, the present invention is set forth in connection with a mechanism of specific structural details, it should be understood that the invention is not in any sense so restricted and that 55 the advantages and benefits thereof are readily obtainable by mechanisms of widely different characters which embody the basic principles of construction and operation and which fall within the scope and spirit of the invention. Therefore, only such limitations should be imposed as are indicated in the 60 appended claims.

In the drawings, Figure 1 is a vertical section, on the line 1—1 in Fig. 2, of feed- 65 mechanism embodying the present inven-

tion; Fig. 2 is a vertical section on the line 2—2 in Fig. 1; Fig. 3 is a perspective view of a strip of sheet-material such as the mechanism in Figs. 1 and 2 is adapted to feed; and Fig. 4 is a perspective view of a polygonal wedge-shaped heel-lift such as may be cut from the strip of Fig. 3 or may be fed by a mechanism substantially the same as that of Figs. 1 and 2.

The invention is illustrated as embodied in mechanism adapted particularly for feeding wedge-shaped strips of sheet-material such as those from which wedge-shaped heel-lifts are cut. In this machine, strips 6 of sheet-material are stacked in a magazine comprising parallel walls 8 and 10, which engage the opposite longitudinal edges of the strips as shown in Fig. 1. The wall 8 is interrupted for a short distance at the bottom, so as to form a space or recess 14 8 opposite the thick and lower edge of the lowermost strip in the stack. The bottom of the magazine is formed by a horizontal plate 12, and the wall 10 is mounted upon this plate by means of lugs 16 which are adjustably fixed on the plate by thumb-screws 18 extending through slots in the lugs. This arrangement permits the wall 10 to be adjusted toward and from the wall 8, and the adjustment is so made that the space between the walls 8 and 10 is less than the width of the strips 6. Accordingly, the strips may be stacked in the magazine in the positions shown in Fig. 1, in which the central planes thereof are in parallelism and 1 in which their thinner edges are higher than their thick edges and are supported by leaning against the wall 10.

The lowermost strip of the stack is separated from the other strips, for the purpose of feeding it, by moving it in the direction of its thick and more advanced edge into the recess 14. For this purpose, I employ two feed-dogs 20, which have toothed extremities adapted to engage the lower surface of the lowermost strip. These dogs are carried at the upper ends of arms 22 projecting rigidly from a rock-shaft 24, which is journaled on the frame of the machine. Each dog 20 is connected with the corresponding arm 22 by a pivot 26, and a spring 28 tends to rock the dog in a direction to throw its toothed end upwardly. This rocking movement is limited, however, by a stop lug 30 on the arm 22. A spring 32, which connects one of the arms 22 with the frame of the machine, tends to swing the arms in a direction to cause the dogs to engage and move the lowermost strip. The opposite movement of the arms and dogs is produced by cam-mechanism. For this purpose, an arm 34, projecting rigidly from the rock-shaft 24, carries a cam-roller 36 which engages a cam 38 fixed on a cam-shaft 40. This shaft may be connected, in any convenient 130

manner, with a suitable source of power so as to rotate it constantly.

The feed-dogs 20 work through openings in the plate 12, and these openings terminate in such a position, as shown by dotted lines in Fig. 1, that when the feed-dogs are in the retracted position shown in the drawings, they engage the ends of the openings and their toothed ends are thereby depressed below the upper surface of the plate 12. When the feed-dogs perform their operative movement, they engage the lower surface of the lowermost strip and move or shift the strip in the direction of its thick end to the position shown in dotted lines in Fig. 1. The dogs then retract and disengage the strip. By this movement of the strip, its thin edge is removed from engagement with the wall 10 of the chute, so that it is permitted to fall by gravity and allow the strip to lie flat upon the plate 12. During this action, the weight of the stack of superposed strips is transferred from a point substantially over the thick edge of the lowermost strip to a point materially forward thereof whereby the lowermost strip is held flat upon the supporting plate 12 in definite position to be removed or fed.

It will be apparent that by a sufficiently long movement of the feed-dogs 20, the strip might be expelled entirely from the stack by the lateral movement above described. In the mechanism illustrated, however, the strip is removed from the stack by an endwise movement following the movement above described. To produce such endwise movement, the mechanism is provided with a table 44 extending from the end of the chute, and a slide-bar 46 moves beneath this table and carries a toothed feed-dog 48 which is pivoted to the slide-bar and is pressed upwardly, at its toothed end, by a spring 52. The feed-dog 48 works through a slot 50 in the plate 12 and the table 44, and when the slide-bar 46 is moved to the right, by any suitable mechanism which need not be here described, the dog 48 engages the lower surface of the strip which has been brought to the position shown in dotted lines in Fig. 1, and pulls it out of the chute, one end-wall 42 of the chute being provided, at the bottom, with an opening, as shown in Fig. 2, to permit this movement of the strip.

An important feature of the operation above described is that the preliminary movement of the lowermost strip, in the direction of its more advanced and lower edge, has the effect of frictionally drawing the next strip above into close engagement with the wall 8, so as to resist the tendency which the falling strip would otherwise have to swing about its upper edge and thus move out of parallelism with the strips above.

Fig. 3 shows one of the strips 6 which the

illustrated mechanism is adapted to feed, and the table 44 may be a part of the machine in which this strip is cut into short pieces, such as that shown in Fig. 4, which may then be used in the construction of heels. It will be apparent, however, that by a mere change in the dimensions of the feed-mechanism, it may be adapted to feed pieces like those of Fig. 4 after they have been formed, either by the cutting of a strip like that in Fig. 3 or in any other manner. Obviously, wedge-shaped pieces in the form of the common dinked heel lifts of curved contour may be readily manipulated in the manner and by the mechanism set forth.

What is claimed as new, is:—

1. A shoe machine for delivering tapering pieces of sheet heel material, having, in combination, means for holding a stack of such pieces and for supporting independently the thin ends of such pieces while the thick ends rest against each other; and separate means for discharging the pieces successively from one end of the stack.

2. A shoe machine for delivering tapering pieces of sheet heel material, having, in combination, means for holding a stack of such pieces by engagement with opposite sides thereof, said pieces having their thick ends contiguous and the thin ends spaced apart to preserve a substantially parallel relation of the pieces; and means for discharging the pieces successively from one end of the stack.

3. A shoe machine for delivering pieces of sheet heel material, having, in combination, a magazine having a bottom support and opposite walls the distance between which is less than the corresponding dimension of the pieces to be delivered, so that the pieces may be stacked therein in positions inclined to the bottom support of the magazine; and means acting on the endmost piece in the stack for separating it therefrom by a lateral movement in the general direction of its more advanced end.

4. A shoe machine for delivering pieces of sheet heel material, having, in combination, a magazine having opposite walls the distance between which is less than the corresponding dimension of the pieces to be delivered, so that the pieces may be stacked therein in a position inclined to the length of the magazine; and means acting on the outer surface of the endmost piece in the stack for separating it therefrom by a movement in a direction substantially normal to the planes of the walls of the magazine.

5. A shoe machine for delivering pieces of sheet heel material, having, in combination, a magazine arranged at a sufficient angle to the horizontal to permit pieces of material stacked therein to descend by gravity, said magazine having a horizontal bottom support and two opposite side walls spaced

- apart a distance less than the corresponding dimension of said pieces so that the pieces are stacked therein in positions inclined to the bottom support; and means for discharging the lowermost piece from the stack.
6. A shoe machine for delivering pieces of sheet heel material, having, in combination, a magazine having opposite walls the distance between which is less than the corresponding dimension of the pieces to be delivered, so that the pieces may be stacked therein in inclined position, one of said walls being interrupted at the bottom of the stack; and means for moving the lower end of the lowermost piece in the stack into the space afforded by the interruption of said wall, so as to permit the opposite end of said piece to fall clear of the other wall of the magazine.
7. A shoe machine for delivering pieces of sheet heel material, having, in combination, a magazine having opposite walls the distance between which is less than the corresponding dimension of the pieces to be delivered, so that the pieces may be stacked therein in inclined position, one of said walls being interrupted at the bottom of the stack; and means for moving the lower end of the lowermost piece in the stack into the space afforded by the interruption of said wall, so as to permit the opposite end of said piece to fall clear of the other wall of the magazine, and for thereafter removing said piece from the magazine by a movement in a direction different from that of its first described movement.
8. Feed-mechanism, having, in combination, a magazine with parallel walls between which strips of sheet-material, wider than the space between the walls, may be stacked in inclined position, one of said walls being interrupted at the bottom of the stack; and means for moving the lowermost strip first laterally into the space afforded by the interruption of said wall, and then longitudinally out of the magazine.
9. A shoe machine for delivering tapering pieces of sheet heel material having, in combination, a magazine having parallel walls for retaining a plurality of said pieces that are stacked therein in inclined and parallel position with their thick ends resting the one against the other and their thin ends resting against one of the walls of said magazine, and means for ejecting the endmost piece.
10. A shoe machine for delivering tapering pieces of sheet heel material having, in combination, means for holding to be fed a plurality of said pieces in stacked and parallel relation with their thick ends in engagement and their thin ends spaced apart comprising means engaging the thick ends and the thin ends of said pieces and acting thereon in the planes of the tapers and means for ejecting the pieces at one end of the stack as they are fed.
11. A shoe machine for delivering tapering pieces of sheet heel material having, in combination, means for holding to be fed a plurality of said pieces in stacked relation and comprising means engaging the respective thick and thin ends of said pieces and acting thereon in the planes of the tapers, and means for successively ejecting pieces at one end of the stack as they are fed.
12. A shoe machine for delivering tapering pieces of sheet heel material having, in combination, means for holding to be fed a plurality of said pieces in stacked relation with their thick ends in engagement and comprising parallelly disposed members acting upon the thick ends and thin ends of said pieces in the planes of the tapers, and means for ejecting the pieces at one end of the stack as they are fed.
13. A shoe machine for delivering tapering pieces of sheet heel material having, in combination, means for holding to be fed a plurality of said pieces in stacked relation with their thick ends in engagement, and means acting transversely of the stack for engaging the pieces at one end thereof and positively ejecting them as they are fed.
14. A shoe machine for delivering uniformly tapering pieces of sheet heel material having, in combination, means for holding to be fed a plurality of said pieces in stacked relation with their central planes in parallelism, and means for engaging the successive pieces as they are fed and positively removing them from the holding means.
15. A shoe machine for delivering uniformly tapering pieces of sheet heel material having, in combination, means for holding to be fed, a plurality of said pieces in stacked face-to-face relation with the central plane of each piece bearing a fixed relation to the central planes of the contiguous pieces and for definitely determining the removal position of said pieces and means for engaging the successive pieces as they are fed into the removal position and removing them from said holding means.
16. A shoe machine for delivering uniformly tapering pieces of sheet heel material having, in combination, means for holding to be fed a plurality of said pieces in stacked face-to-face relation and for definitely determining the removal position of said pieces, and means for removing the positioned pieces at one end of said holding means.
17. A shoe machine for delivering uniformly tapering pieces of sheet heel material having, in combination, means for holding a stack of indeterminate length of said pieces that are disposed in face-to-face re-

lation and are maintained in fixed relationship as they are fed through said holding means, and separate means for removing the pieces as they are fed to one end of the 5 stack.

18. A shoe machine for delivering uniformly tapering pieces of sheet heel material having, in combination, means for holding a stack of indeterminate length of said 10 pieces that are disposed in face-to-face relation with their thick ends in engagement and maintainig such relationship as they are fed, and means for engaging the successive pieces as they are fed to one end of the 15 stack and laterally and positively ejecting them therefrom in the plane of the articles.

19. A shoe machine for delivering uniformly tapering pieces of sheet heel material having, in combination, means for holding to be fed a plurality of said pieces in stacked 20 face-to-face relation with their respective thick ends and thin ends positively supported throughout the feeding operation, means for definitely determining the removal position of said pieces, and means for removing the successive pieces as they are fed 25 into said removal position.

20. A shoe machine for delivering tapering pieces of sheet heel material having, in 30 combination, means constructed and arranged to hold and maintain as they are fed a stack of indeterminate length of said pieces that are disposed in face-to-face parallel relation with their thin ends spaced 35 apart, and means for successively removing said pieces as they are fed to one end of the stack.

21. The method of feeding tapering pieces of sheet heel material which comprises arranging a plurality of said pieces in a stack 40 of indeterminate length and in face-to-face relation with their central planes in parallelism and their thin ends spaced apart, feeding the stack of pieces in the direction of its 45 length while maintaining the pieces in fixed mutual relationship, and removing the successive pieces from the end of the stack to which they are fed.

22. A shoe machine for delivering tapering pieces of sheet heel material having, in 50 combination, means for holding a stack of said pieces in parallel relation throughout the greater portion of its length and for successively modifying the positions of the 55 pieces as they approach the end of the stack, and means for successively removing the endmost pieces from the holding means.

23. A shoe machine for delivering tapering pieces of sheet heel material having, in 60 combination, means for holding a stack of said pieces in parallel relation throughout the greater portion of its length and for successively laterally shifting the pieces in the direction of their thick ends as they ap-

proach the end of the stack, and means for 65 engaging the successive endmost pieces and removing them from the holding means.

24. A shoe machine for delivering tapering pieces of sheet heel material having, in combination, means for holding throughout 70 the greater portion of its length a plurality of said pieces in alined and stacked parallel relation, and for successively shifting the pieces laterally in the direction of their thick 75 ends as they approach the end of the stack to transfer the weight of the stack and cause the endmost piece to lie flat in a definite removal position, and means for removing the endmost piece so positioned.

25. A shoe machine for delivering tapering pieces of sheet heel material having, in combination, means for holding to be fed a stack of said pieces disposed in parallel relation, a support for the lowermost piece of the stack, and means for causing the weight 85 of the stack to act upon the lowermost piece forward of the thick end thereof and hold it flat in definite position upon the support.

26. A shoe machine for delivering tapering pieces of sheet heel material having, in 90 combination, means for holding to be fed a stack of said pieces disposed in parallel relation, a support for the lowermost piece of the stack, means for causing the weight of 95 the stack to act upon the lowermost piece forward of the thick end thereof and hold it flat in definite position upon the support, and ejecting means laterally movable in a plane, immediately above said support for engaging and removing the endmost piece 100 definitely positioned thereon.

27. A shoe machine for delivering tapering pieces of sheet heel material having, in combination, a support, a magazine above 105 said support for holding to be fed a stack of said pieces disposed in parallel relation, said magazine having an offset portion at its lower end to permit the successive lowermost pieces in the stack to lie flat upon said support, and means for successively removing 110 the flatly positioned pieces upon said support.

28. A shoe machine for delivering uniformly tapering pieces of sheet heel material having, in combination, means for holding 115 to be fed a plurality of said pieces in stacked parallel relation, means acting upon each endmost piece of the stack for shifting it laterally in the direction of its thick end, and means for removing the shifted end- 120 most piece from the holding means.

29. The method of feeding tapering pieces of sheet material which comprises arranging a plurality of said pieces in a stack of indeterminate length and in face-to-face relation 125 with their central planes in parallelism, feeding the stack of pieces in the direction of its length while maintaining the pieces in

parallelism, and removing the successive pieces from the end of the stack to which they are fed.

30. The method of feeding tapering pieces of sheet heel material which comprises arranging a plurality of said pieces in a stack of indeterminate length with the central plane of each piece bearing a fixed relation

to the central plane of each contiguous piece, feeding the stack of pieces in the direction of its length while maintaining the pieces in fixed mutual relationship and removing the successive pieces from the end of the stack to which they are fed.

FRED V. HART.

It is hereby certified that in Letters Patent No. 1,352,747, granted September 14, 1920, upon the application of Fred V. Hart, of Lynn, Massachusetts, for an improvement in "Feed Mechanism," an error appears in the printed specification requiring correction as follows: Page 5, line 116, claim 28, first occurrence, strike out the word "to"; and that the said Letters Patent should be read with this correction therein that the same may conform to the record of the case in the Patent Office.

Signed and sealed this 2nd day of November, A. D., 1920.

[SEAL.]

L. B. MANN,
Acting Commissioner of Patents.

Cl. 12—42.
